FISHING LINE HOLDER

Oliver L. Ayers, Alexandria, Va., assignor to Lascor Incorporated, Harpers Ferry, W. Va., a corporation of Maryland

Filed July 13, 1964, Ser. No. 80,823

Term of patent 14 years

(Cl. D31—4)

I claim:

The ornamental design for a fishing line holder, as shown.
